UNITED STATES PATENT OFFICE.

DAVID COLE AND JULIUS G. BERGMAN, OF EL PASO, TEXAS.

GRINDING MILL.

Application filed April 6, 1922. Serial No. 550,016.

To all whom it may concern:

Be it known that we, DAVID COLE, a citizen of the United States, and JULIUS G. BERGMAN, a subject of the King of Sweden, residing at El Paso, in the county of El Paso and State of Texas, have invented certain new and useful Improvements in Grinding Mills, of which the following is a specification.

10 This invention relates to grinding mills and particularly to grinding mills of the rod type. Certain features of the invention are applicable to mills of other types, and are capable of general use wherever a rotary drum or cylinder must be supported on a peripheral bearing.

15 Rod grinding mills consist of an elongated cylindrical drum, rotatable on a horizontal axis, and containing a large number of 20 loose parallel rods of steel lying horizontally in the drum and extending substantially the entire length of the drum. When the drum is rotated the tumbling of the rods performs the grinding function, and such mills 25 are coming into extensive use for grinding ores.

20 Rod grinding-mills are peculiarly desirable because of their superior grinding action but their construction and operation 30 have heretofore presented serious difficulties which arose from the great weight of the loaded grinding drum, and the practical necessity of having at least one removable head. The purpose of the removable head 35 is to permit the mill to be run slowly with the rods exposed so that the rods can be inspected, and worn rods can be removed. Worn rods are likely to become bent and snarled with troublesome results, and quick 40 and easy inspection is essential to practical and economical operation.

25 A removable head may be had by eliminating one of the end trunnions common in grinding mills, and substituting a riding ring and supporting rollers. Since supporting rollers have only line contacts with the riding ring a large number of rollers must be used to avoid excessive crushing stresses on the lines of contact between rollers and riding rings. The use of more than 30 two rollers makes necessary some load equalizing means. Lever equalizers can be used, but their construction is expensive and is prohibitively expensive except with a very 35 small number of rollers. It is hard to secure

40 accurate alinement of the rollers, and harder still to maintain it under the conditions of actual service. Even slight mis-alinement of a supporting roller, leads to destructive wear and serious waste of power, under the heavy 45 loads encountered in this service.

45 Another difficulty incident to the use of rod grinding mills is the fact that the wear on both rods and lining is greater at the feed end than at the discharge end, so that 50 it has been the practise heretofore to reverse the rods and lining in the drum at intervals to equalize the wear. This is a laborious and expensive operation.

50 The present invention overcomes these difficulties by providing a self-equalizing type of bearing in which the stresses are all favorable to the maintenance of alinement. Stated broadly, the invention contemplates the use of a riding ring or rings running 55 on a series of rollers, such series of rollers being supported on or between link chains adjustably mounted at their ends and properly stabilized to prevent rocking or pitching of the supported drum. All the rollers, 60 roller supporting bearings, hinge pins, and chain links may be made interchangeable, and may be so standardized as to be capable of use in mills of this type differing considerably in size. These characteristics permit 65 accurate and yet inexpensive manufacture. The simplicity of the chain structure permits the use, without undue complication or expense, of a relatively large number of rollers and this so reduces the load per roller 70 that it is possible to avail of commercial sizes of ball or roller bearings. This makes the use of antifriction bearings economically 75 possible and leads to the saving of about one third of the power otherwise 80 necessary.

75 While one equalizing roller bearing of the type herein disclosed and claimed may be used with that type of mill having one riding ring and one trunnion bearing, the full 80 advantages of the invention are secured by using two equalizing bearings and two riding rings and dispensing with trunnions altogether. It then becomes possible to make the drum symmetrical with respect to its 85 transverse median plane and to design the feed and discharge fittings so that they may be transposed. A drum so constructed may be lifted from its bearings, turned end for end, and mounted in reversed position on 90

the bearings. This can be accomplished in a few minutes with the crane equipment usually available, and, after the interchange of the feed and discharge fittings has the 5 same effect as the reversal of the lining and rods, as well as the additional beneficial effect of reversely meshing the driving pinion and ring gear. Since the continuous operation of many plants is largely dependent 10 on the continuous operation of the grinding mills the practical importance of the above feature is manifest.

Preferred embodiments of the invention are shown in the accompanying drawings, in 15 which :-

Fig. 1 is a side view partly in elevation and partly in axial section of the complete mill.

Fig. 2 is a section on the line 2—2 of 20 Fig. 1.

Fig. 3 is an elevation of a chain carrier yoke with chain and rolls attached, showing the arrangement of the chain stabilizers.

Parts of this figure are broken away to show 25 how the chain carrier yoke is adjusted.

Fig. 4 is a plan view of the parts shown in Fig. 3.

Fig. 5 is a section on an enlarged scale taken on the line 5—5 of Fig. 3.

30 Fig. 6 is a fragmentary view, similar to a portion of Fig. 2, but showing a modified construction.

Fig. 7 is a fragmentary plan of the supporting roll structure shown in Fig. 6.

35 Fig. 8 is an end elevation of the supporting roll structure shown in Fig. 6.

The cylindrical grinding drum is made up of four substantially identical flanged sections 11 bolted together and two identical 40 removable heads 12. The ring driving-gear 13 is mounted with its web 14 clamped between the flanges of the two middle sections 11, and two identical riding rings 15 are each similarly mounted with their webs 16 45 clamped between the flanges of a corresponding end section 11 and the adjacent one of the two middle sections 11. The feed scoop 17 and the discharge fitting 18 are interchangeable with each other and are removably mounted by means of bolts or the equivalent. This produces a structure 50 which is symmetrical with reference to the median plane of gear 13, except for the feed scoop 17 and fitting 18, and hence may be turned end for end on its supporting 55 bearings. The feed scoop 17 and fitting 18 may be interchanged with each other as conditions require.

Any suitable form of lining 19 may be 60 used and this may be removably mounted in any suitable manner, for example by studs with nuts 20 (see Fig. 2). The drive mechanism may be of any desired type, and is shown as consisting of pinion 22 on the motor shaft, gear 23 meshing therewith, and

pinion 24 fast on a shaft with gear 23 and meshing with ring gear 13.

The riding rings 15 run on corresponding sets of rollers each set supported by two equalizing chains. Two slightly different 70 embodiments of this inventive concept are shown in the drawings and that illustrated in Figs. 1 to 5 inclusive will first be described.

The main base frame is shown at 25 and 75 upon this are mounted two identical cast frames 26. The frames 26 each carry a corresponding bearing structure and as these bearing structures are alike a description of one will suffice.

Mounted at opposite ends of each frame 26 are the two chain carrier yokes 27. Each of these has a base plate 28 and two inclined upstanding arms 29. The arms 29 are connected by a cross bar 30 which serves as a journal for the end links of the chains and as a journal for the guide or steadyng disc 31.

There are two identical chains, each made up of single-plate links 32 and double-plate links 33, arranged in alternation. Successive links of each chain are connected together by pins 34 which are common to the two chains. Each pin carries between the two chains a roller 35, the preferred construction being shown in Fig. 5. The pins 34 are shouldered near their ends at 36 and against the shoulders 36 cap discs 37 are held by nuts 38. Certain of these cap discs are modified by having stabilizing tension 90 members formed integrally with them, as will be further described. The links 32 and 33 are held between discs 37 and shoulders 39. The inner races of two annular ball 95 bearings 40 are held against shoulders 41 by sleeves 42 threaded on pins 34 between shoulders 39 and 41. The outer races of the bearings 40 are held in annular pockets in the opposite ends of rollers 35 by retaining rings 43. These are held by cap screws 44 100 or the equivalent, and are provided with grooves which confine dust-excluding washers 45 in contact with the outer cylindrical surfaces of sleeves 42. Various other constructions might be used, depending in some 105 degree on the particular type of bearing adopted.

Each yoke 27 is adjustable toward and from the other, being held to frame 26 by bolts 46 which pass through slots in base plate 28. The thrust is taken by screws 47 which serve also as means to secure accurate adjustment. The parts are so designed that the rollers will conform to the corresponding riding ring 15 with the discs 31 in contact with the riding ring 15. Adjustment of the carrier yokes insures the accurate adjustment of each chain and makes it possible to establish the correct relation between the chains and the drum, in which the axes 115 120 125 130

of all the rollers are parallel to the axis of the drum.

The discs 31 are not designed to carry load, but merely serve as measuring devices, indicating when the distance from riding ring to center line of chain support is correct. These discs are preferably made of flexible material. Near the ends of the chain, radial tension bolts 48 are used as stabilizers. These are preferably integral with the caps 37 forming part of the first joint of the chain (counting from the ends). They act in tension only, the nuts 49 bearing against yoke 27 and the bolt being free to slide downward through the yoke.

Similarly the next hinge joint is held down by stop screws 50 acting against the caps 37 of that joint. The screws 50 are locked by check nuts as shown.

Finally the middle link of the chain is stayed horizontally by bolts 51 which like the bolts 48 are preferably integral with the caps 37 on the hinge pins at the ends of this link. These bolts act in tension only, their action being adjusted by means of nuts 52.

The stabilizing members 48, 50 and 51 do not prevent the rollers 35 from moving outward beyond their normal positions, but they are so adjusted as to resist movement inward or upward beyond the normal positions. Thus the chain is free to assume the normal curvature under load, so that no single roller or pair of rollers can be overloaded. At the same time the rollers are restrained against abnormal inward or upward movement such as would tend to cause or facilitate rocking of the drum.

When the two bearing structures are aligned with reference to the axis of the drum there is an inherent tendency to maintain alignment and equalized or substantially equalized load on all rollers.

In Figs. 6, 7 and 8 a structure is illustrated which includes the supporting chains, but stabilizes the chains without use of any restraining members acting on the chain between its end supports, such as those used in the structure of Figs. 1 to 5 inclusive.

In the structure of Figs. 6 to 8 base castings 55 serve the same general purpose as the base castings 26 of Figs. 1 to 5. At each of their ends they are formed with two spaced horizontal brackets 56 and two aligned seats 57 for thrust journals 58. Mounted on the journals 58 are yoke structures each consisting of two thrust members 59 connected rigidly with each other by a bar 60. Upward or inward movements of the yoke structures are adjustably limited by stop bolts 61 which pass through thrust members 59 and brackets 56. Downward or outward movements of the yoke structures are cushioned by shock absorbing springs 62 which surround the bolts 61 and are interposed between thrust members 59 and brackets 56.

Each yoke structure has two stop bolts 61 and two shock-absorbing springs 62 as is clearly indicated in Figs. 7 and 8.

As in the case of the structure of Figs. 1 to 5, the riding ring 15 of the grinding drum 70 runs on a series of rollers 35 sustained by two chains made up of alternating single-plate links 32 and double plate-links 33. The structure of the rollers and their bearings has been described with reference to Fig. 5.

At their opposite ends both chains are pivotally connected to equalizing plates 63 which are journaled on the bars 60. Rollers 35 are mounted on the hinge pins connecting the chains to the plates 63 exactly as if plates 63 were ordinary links in the chain. The equalizing plates 63 extend beyond the bars 60 and are rigidly connected together in pairs by bars 64 which are shouldered and provided with nuts 65. On the bars 64 are mounted rollers 66 which are identical with rollers 35 and which are mounted on bearings identical with those used for rollers 35. In fact the only difference is that the bar 64 (unlike the pins 34) serves as a rigid connection between the plates 63 and obviously has no hinging function.

An examination of Fig. 6 will make clear the fact that the lines of pull of the chain 95 on bars 62 pass below the axes of journals 58 so that the resultant effect is a tendency to swing thrust members 59 downward against the thrust of springs 62. Each pair of springs 62 is however of sufficient aggregate strength to resist this stress, plus the stress exerted directly by the loaded drum against the rollers carried by the equalizing plates 63. The stop bolts 60 are so set as to prevent the upward movement of the thrust members 59 beyond normal load supporting position.

The effect of this arrangement is that each pair of equalizing plates 63 together with the rollers directly carried thereby and also rollers on adjacent portions of the chain, may move downward from normal position against a spring buffer in the event of excessive load. The equalizing plates are, however, positively limited in their upward movement by bolts 60 and hence cannot follow the drum upward beyond normal position. Consequently there is no tendency to cause or permit the drum to rock or pitch.

Both types of construction have in common the idea of supporting the drum on a series of chain-sustained rollers and both embody the idea of stabilizing the chains by restraining means which limit the upward or inward movement of the chain loop or portions thereof, without restraining outward movements. Since each roller is free to move outward if subjected to undue stress, and since the effect of such outward movement is immediately to distribute the excess load 130

among the remaining rollers the structure as a whole acts to equalize the load among the rollers under all conditions.

The advantage of the reversible drum 5 may be had by the use of two riding rings but the advantages of the self-equalizing bearing may be had, wherever a riding ring is used, and we contemplate the use of this bearing in any type of mill using one or 10 more riding rings, and generally to support any rotary shell or member whose form is such as to render the use of a riding ring desirable.

In certain of the claims we use the term 15 "inward movement" to define motion of the rollers toward the axis of the drum and the term "tangential movements" to define motion of the rollers in a direction approximately tangential to the riding ring. These 20 terms are used in a general sense only, for lack of better terms, and are not to be interpreted in their strict sense, for obviously the rollers do not necessarily move in straight lines nor is their motion strictly radial or 25 tangential. The terms do, however, express the general directions of the restraining action of the stops.

What is claimed is:—

1. The combination with a rotary drum 30 of a flexible supporting member suspended in arcuate form between points adjacent its ends, and a plurality of rolling anti-friction elements sustained by said supporting member in rolling contact with said drum.

35 2. The combination with a rotary drum of a flexible supporting member suspended in arcuate form between points adjacent its ends, and a plurality of rolling anti-friction elements interposed in load bearing relation between said supporting member and drum, and constructed and arranged to operate in rolling contact with both.

3. The combination with a rotary drum of a flexible supporting member suspended 45 in arcuate form between points adjacent its ends; a plurality of rolling anti-friction elements sustained by said supporting member in rolling contact with said drum; and stabilizing means serving to prevent said drum 50 from rocking.

4. The combination with a rotary drum of a flexible supporting member suspended in arcuate form between points adjacent its ends; a plurality of rolling anti-friction elements interposed in load bearing relation between said supporting member and drum, and constructed and arranged to operate in 55 rolling contact with both; and stabilizing means serving to prevent said drum from 60 rocking.

5. The combination with a rotary member; of a self-equalizing bearing therefor, comprising in combination a pair of supports spaced apart; a flexible member sus- 65 pended in arcuate form between said sup-

ports; and a plurality of rollers rotatably mounted on said flexible member in load sustaining relation with said rotary member.

6. The combination with a rotary member; of a self-equalizing bearing structure 70 comprising a pair of supports spaced apart; a chain structure suspended in arcuate form between said supports and including two spaced parallel series of links, and a series of transverse pins, each pin serving at its 75 opposite ends to hinge together adjacent links of each series; and rollers rotatably mounted on said pins between said parallel series of links in load sustaining relation with said rotary member.

80 7. The combination with a rotary member; of a self-equalizing bearing structure comprising a pair of supports spaced apart; a chain structure suspended in arcuate form between said supports and including two spaced parallel series of links and a series 85 of transverse pins, each pin serving at its opposite ends to hinge together adjacent links of each series; rollers surrounding said pins; opposed bearing races removably mounted in said rollers and on said pins; and anti-friction rolling members interposed between said races.

8. The combination with a rotary drum, 90 of a supporting bearing therefor comprising a flexible member supported at its ends; a plurality of supporting rollers mounted at intervals on said flexible member and in rolling contact with said drum; and stabilizing means serving to prevent said drum from 95 rocking.

9. The combination with a rotary drum, 100 of a supporting bearing therefor, comprising a chain supported at its ends and including a series of links and a series of hinge pins connecting said links; a series of rollers journaled on said hinge pins and in rolling contact with said drum; and stabilizing means serving to prevent said drum from 105 rocking.

110 10. The combination with a rotary drum, of a supporting bearing therefor, comprising a pair of supports; a chain suspended in a loop between said supports and including a series of links and a series of hinge pins connecting said links; a series of rollers journaled on said hinge pins and in rolling contact with said drums; stabilizing means carried by said supports acting on said chain and serving to prevent said drum from rocking; and means for adjusting said stabilizing means.

115 11. The combination with a rotary drum, of a supporting bearing therefor, comprising a flexible member supported at its ends; a plurality of rollers rotatably mounted at intervals on said flexible member, and in rolling contact with said drum; and a stop or stops serving to limit the movement of one or more of said rollers in a direction to 120 125 130

ward the axis of the drum, while permitting motion in the opposite direction.

12. The combination with a rotary drum, of a supporting bearing therefor, comprising a chain including a series of links and a series of hinge pins connecting said links; a series of rollers journaled on said hinge pins and in rolling contact with said drum; and stops preventing the motion beyond their normal position of certain of said hinge pins adjacent the ends of said chain, in a direction toward the axis of said drum while leaving them free to move in the opposite direction.
13. The combination with a rotary drum, of a supporting bearing therefor, comprising a pair of adjustable supports, a chain structure connected at its ends to said supports and suspended between the same, and a plurality of rollers rotatably mounted at intervals on said chain structure, and in rolling contact with said drum.

14. The combination with a rotary drum, of a supporting bearing therefor, comprising a pair of adjustable supports, a chain structure connected at its ends to said sup-

ports and suspended between the same, a plurality of rollers rotatably mounted at intervals on said chain structure, and in rolling contact with said drum; and limit stops serving to limit the movement of certain of said rollers in the general direction of the axis of said drum without limiting this movement in the opposite direction.

15. The combination with a rotary drum, of a supporting bearing therefor, comprising a pair of adjustable supports, a chain structure connected at its ends to said supports and suspended between the same, a plurality of rollers rotatably mounted at intervals on said chain structure and in rolling contact with said drum; and limit stops certain of which limit the inward movements of rollers adjacent the ends of the chain and others of which limit (tangential) movements of rollers adjacent the middle of the chain, all said stops permitting movement outward by said rollers.

In testimony whereof we have signed our names to this specification.

DAVID COLE.
JULIUS G. BERGMAN.
